The ornamental design for a automobile radiator grille, as shown and described.

DESCRIPTION

FIG. 1 is a front elevational view of a automobile radiator grille in accordance with our new design;

FIG. 2 is a top plan view of the automobile radiator grille in accordance with our new design of FIG. 1;

FIG. 3 is a bottom plan view of the automobile radiator grille in accordance with our new design of FIGS. 1 and 2;

FIG. 4 is a left side elevational view of the automobile radiator grille in accordance with our new design of FIGS. 1 to 3;

FIG. 5 is a right side elevational view of the automobile radiator grille in accordance with our new design of FIGS. 1 to 4;

FIG. 6 is a front-right-top side perspective view of the automobile radiator grille in accordance with our new design of FIGS. 1 to 5; and,

FIG. 7 is a front-left-bottom side perspective view of the automobile radiator grille in accordance with our new design of FIGS. 1 to 6.

The broken line illustrate portions of the automobile radiator grille in which the design is embodied that form no part of the claimed design.
